Primary Examiner — Janice Patyk*Assistant Examiner* — Kendra L Hebel(74) Attorney, Agent, or Firm — Phillip Black; Dossey & Jones PLLC(57) CLAIM

The ornamental design for a lid, as shown and described.

DESCRIPTION

FIG. 1 is a front view of the lid shown in an environment of use;

FIG. 2 is a top view of the lid;

FIG. 3 is a side view thereof;

FIG. 4 is a cross sectional side view thereof; and,

FIG. 5 is a cross sectional top view thereof.

The contrast in shading represents a contrast in appearance only and does not represent any particular color, material, texture or finish. The broken lines are for illustration only and do not form a part of the claimed design.
